UNITED STATES PATENT OFFICE

96,666

DESIGN FOR A HAND BAG MIRROR OR SIMILAR ARTICLE

Samuel Herman, New York, N. Y.

Application July 9, 1935, Serial No. 57,572

Term of patent 3½ years

To all whom it may concern:

Be it known that I, Samuel Herman, a citizen of the United States, and resident of New York city, in the county and State of New York, have invented a new, original, and ornamental Design for a Hand Bag Mirror or Similar Article, of which the following is a specification, reference being had to the accompanying drawing, forming a part thereof, and of which Figure 1 is a view in front elevation; Fig. 2 is a view in edge elevation; Fig. 3 is a top plan view; Fig. 4 is a view in vertical section taken on the line 4—4 of Fig. 1; and Fig. 5 is a view in horizontal section taken on the line 5—5 of Fig. 1, of a hand bag mirror or similar article, showing my new design.

The design consists essentially in the ornamental top portion of the mirror or similar article.

I claim:

The ornamental design for a hand bag mirror or similar article substantially as shown and described.

SAMUEL HERMAN.
